MOTION PICTURE CAMERA

Norman R. Kubnick, Wheeling, Allen R. Obergfell, Niles, and Grant D. Ross, Jr., Chicago, Ill., assignors to Bell & Howell Company, Chicago, Ill., a corporation of Illinois

Filed May 21, 1964, Ser. No. 80,099

Term of patent 14 years

(Cl. D61—1)

Fig. 1

Fig. 2.

The bottom of the motion picture camera is substantially plain and unornamented.

We claim:

The ornamental design for a motion picture camera, as shown and described.
